Term of patent 14 years

(Cl. D44—15)

FIG. 1.

FIG. 2.

FIG. 3.

FIG. 4.

FIG. 5.

FIG. 1 is an elevational view of a tureen showing my new design wherein the species is characterized by a pair of circumferential bands of facets, one band adjacent the lip and one band adjacent the lower portion;

FIG. 2 is a top plan view;

FIG. 3 is an enlarged scale fragmentary elevational view of the band of facets;

FIG. 4 is a sectional view on line 4—4 of FIG. 3; and

FIG. 5 is an elevational view of a tureen showing my new design wherein the species is characterized by a bead adjacent to and spaced from the lip and a circumferential band of facets adjacent the lower portion.

The design is generally characterized by two circumferential ornamenting bands, one adjacent the lip and one adjacent the lower portion as shown.

A portion of FIG. 1 is shown broken away for convenience of illustration, while a cover is shown by broken lines in FIG. 1 for illustrative purposes only.

I claim:

The ornamental design for a tureen, substantially as shown and described.
